FLUID COOLING APPARATUS AND METHOD

George M. Kleucker, St. Louis, Mo.

Application October 19, 1936, Serial No. 106,308

22 Claims. (Cl. 62—126)

This invention relates generally to fluid-cooling apparatus and, more particularly, to apparatus adapted for the cooling of liquids, such as beer, milk, water, and the like.

5 My present invention has for an object the provision of an apparatus and method for the cooling of fluids, such as beer, milk, water, and the like, in a sanitary and efficient manner, and in such manner to utilize the maximum coefficient of heat transfer.

10 My invention has for another object the provision of an apparatus and method for the cooling of fluids and particularly liquids in which the cooling medium or refrigerant is re-circulated in liquid state either by means of differential pressures without the intervention of a recirculation pump, by means of a mechanically actuated circulating pump, or any other means whether used singly or combined.

15 My invention has for still another object the provision of an apparatus and method for the cooling of fluids and liquids in which the heat exchanger or cooler is of a unitary construction that may be thoroughly cleaned between cooling operations.

20 My invention has for a further object the provision of an apparatus and method for the cooling of fluids and more particularly liquids in which the heat exchanger is entirely leak-proof and which may be cleansed at high temperatures without fear or danger of producing leaks or permanent distortion therein.

25 Other objects and advantages of the present invention will appear more fully from the following detailed description, which, taken in connection with the accompanying drawings, will disclose to those skilled in the art the construction and operation of a preferred form of the present apparatus, in which drawings,—

30 Figure 1 is a cross-sectional elevational view of an apparatus embodying my invention;

35 Figure 2 is a cross-sectional plan view of the apparatus taken approximately on the line 2—2, Figure 1;

40 Figure 3 is a cross-sectional elevational view of a portion of the apparatus illustrated in Figure 1, showing, in part, a modified form of apparatus of my invention; and

45 Figure 4 is a cross-sectional plan view taken approximately on the line 4—4, Figure 3.

50 Referring now more in detail and by reference characters to the drawings, the apparatus generally designated A comprises a shell 1, which is fabricated preferably from steel or other suitable material adapted to retain pressures. Pro-

vided in the bottom wall of shell 1, is an opening 2, communicating with which is a shell 3 forming a sump B, the shell 3 being constructed either integrally with the shell 1 or separately and rigidly welded thereto.

5 Figure 1 is a retaining collar or flange integrally formed or welded rigidly to the shell 1 at its upper extremity, and a bell-shaped top member or wall 5 is provided with a companion flange or collar 6 adapted for interlocking engagement with the flange 4 to provide a complete top closure for the shell 1. As shown in Figure 1, the flange members 4 and 6 are drawn together into fluid and gas tight sealing engagement by means of suitable bolts 7, and two packing glands 10 and 11 providing gas-tight entrance and exit, respectively, to and from the shell 1 are disposed on the bell-shaped top wall 5. Another packing gland 12 providing gas-tight entrance into the lower part of the shell 1 is disposed on the bottom of the shell, and a helical refrigerant pre-cooling coil 13 is disposed within the shell 1 substantially as shown, the inlet end of the coil 13 entering the shell 1 through the gland 10.

10 A helical heat exchanger coil 14 is also disposed within the shell 1 substantially as shown, the inlet end of coil 14 entering the shell 1 at its lower end through the packing gland 12 and the outlet end of the coil 14 leaving the shell 1 through the packing gland 11.

15 The coil 14 is disposed concentrically about the pre-cooler coil 13 and is preferably of continuous seamless tube construction, thereby affording a readily cleanable one-piece surface internally of the evaporator.

20 Mounted above, and being substantially of the same diameter for registration with, the coil 14, is an annular refrigerant trough 16 preferably of U-shape in section, the trough 16 being formed on the center line of its bottom or end wall with an annular series of evenly spaced orifices 17 each preferably of such selected dimensions to permit the circulated liquid refrigerant to fill the trough to a certain height, thereby building up some head on the bottom for constant even flow. Preferably also the trough side walls are provided with depending extensions for confining the spraying refrigerant for coil engagement, such wall extensions following the contour of the upper member of the coil 14 and at their lower margin being serrated or otherwise evenly spaced from the coil for corresponding uniform distribution of the refrigerant. It should be understood, however, that the present invention is not limited to any particular means for

5

15

20

25

30

35

40

45

50

55

the uniform distribution of liquid refrigerant, such as the trough above described, as other means may also be employed for accomplishing the same purpose. Furthermore, depending on the size and capacity of the cooler, I may utilize a plurality of heat exchange coils, together with suitable associated pre-cooling coils and liquid refrigerant distribution means.

At its lower end, the pre-cooler coil 13 has pressure-tight connection through a union 18 with the upper end of a pipe 19, which vertically extends downwardly into the sump B for connection with a horizontally disposed pipe 20 extending outwardly through the wall of shell 3 to an expansion valve 21 connected on its other side to a pipe 22. The latter returns through the wall of the sump-casing 3 and is connected to a pressure nozzle 23, access to which is provided by a flanged opening 24 preferably located opposite 20 a port-hole member 25.

As shown, an intake orifice 26 of a Venturi tube 27 is disposed opposite the pressure nozzle 23, the tube 27 being connected at its outlet orifice end to a refrigerant circulation pipe 28, which extends upwardly angularly through the sump B and then vertically inside the main shell 1 to a distributor head 29.

A plurality of horizontal refrigerant distributing pipes 30 extend radially outwardly from the distributor head 29 and terminate at points directly over the open top of the trough 16, suitable downwardly opening elbows 30' being provided at the extremities of the pipes 30 for directing the flow of the refrigerant downwardly therefrom and into the trough 16, or other suitable distributor.

If a mechanically actuated pump is used, or other means for circulating the liquid refrigerant, a pre-cooling coil is not required. It will then only be necessary to feed the liquid refrigerant directly into the sump, preferably by means of a float control valve.

A main gas return line 31 projects through the top wall 5 to open at an end into the main shell 1, the line 31 being connected at its other end to one side of a back pressure control valve 32 connected, in turn, at its other side to one side of a suction valve 33. On its other side, the valve 33 is connected to a suction line 34, which, in turn, is connected to the low pressure or suction side of a suitable refrigeration system of conventional design (not shown).

An auxiliary safety gas return line 35 also projects at an end through the top wall 5 into shell 1 and is connected through a safety pressure relief valve 36 to the line 34 at a point beyond the suction stop valve 33.

The sump B is provided at its bottom with an oil drop leg 37, communicating with which is an oil drain valve 38, all as best seen in Figure 1. The sump B is also provided with a separate liquid refrigerant supply line 39 preferably float-controlled, by which the sump B is filled with liquid refrigerant to a level well above the intake orifice 26 of the Venturi tube 27. When the expansion valve 21 is opened, the suction created at the intake orifice 26, as above described, will draw a substantial quantity of liquid refrigerant through the tube 27 and intermingle it with the refrigerant coming from the jet out of the pressure nozzle 23. And, in order to increase the heat transfer of the liquid refrigerant pre-cooling coil 13, the coil 13 may also be provided 75 with a liquid distributing trough or device sim-

ilar to the trough 16 associated with the heat exchanger coil 14.

It may be desirable under certain circumstances and conditions to provide a multi-stage expansion nozzle operation such as that shown in Figure 3. Such a multi-stage device comprises a vertical pipe 40, which corresponds to the vertical pipe 19, and is likewise connected to the bottom of the precooler coil 13 through the union member 18. The pipe 40 is also connected to a horizontal pipe 41, which passes outwardly through the wall of the sump shell 3 and is connected to an expansion valve 42. The latter is connected at its outlet side to a return horizontal pipe 43, which returns inwardly through the wall of the sump shell 3 and branches into two pressure nozzle supply lines 44 and 45, to which are connected two pressure nozzles 46 and 47, respectively, the pressure nozzle 46 having a Venturi tube 50 juxtaposed thereto. Access to pressure nozzle 46 is provided by a flanged opening 51, as previously described in connection with Figure 1. Similarly, a port-hole member 52 is provided adjacent the flanged opening 51.

At its outlet orifice, the Venturi tube 50 enters into a vertical leg 53, which extends outwardly from the intake orifice 54 of a second Venturi tube 55. The pressure nozzle 47 extends upwardly through the vertical leg 53 to a point opposite the intake orifice 54 of the tube 55. It is preferable that the pressure nozzle 47 be located above the point of entrance of the Venturi tube 50 into the leg 53, as shown.

Access to pressure nozzle 47 is provided by a flanged opening 56, and a port-hole member 57 is provided in the side of the sump shell 3 at a point adjacent the opening 56. The multi-stage expansion nozzle operation is not limited to the design shown in Figure 3, wherein the second Venturi tube is connected at right angle to the first one. It may be preferable, and under certain conditions more desirable, to arrange the tubes in progressive series, so that they are in line with the flow in order to prevent friction losses, as the main object of multi-staging is to build up pressure at the discharge of the recirculated refrigerant. The recirculating device previously described, both of the single effect as well as multi-stage effect, located in sump B need not be an integral part of shell 1, but may also be arranged as a separate part of the apparatus constituting the main evaporator, depending on conditions. An oil drop leg 58 may also be provided in this embodiment in the same manner as described in connection with Figure 1.

In operation, the liquid or fluid to be cooled enters the heat exchanger coil 14 at the bottom thereof through the portion engaged in the packing gland 12, passes upwardly through the interior of the coil, and leaves the coil through the top portion thereof, which is engaged in the gland 11. Liquid refrigerant, such as ammonia, freon, and the like, enters the precooler coil 13 through the top portion thereof, which is engaged in the gland 10, and passes downwardly through the interior of the coil. The refrigerant flows downwardly through coil 13 and through the vertical pipe 19 and out to the expansion valve 21, which is adjusted to a predetermined setting providing for the requisite amount of the refrigerant. The high pressure refrigerant passes outwardly from the expansion valve 21 through the pipe 22 to the pressure nozzle 23. The pressure nozzle 23 permits the refrigerant 75

to exit therefrom in a high pressure jet, which enters into the Venturi tube 27 at high velocity. The pressure and velocity of the refrigerant passing through the Venturi tube 27 is considerably higher than the pressure surrounding its intake orifice 26, such differential in pressures creating a suction through the intake orifice 26 of the Venturi tube 27.

The expanded liquid refrigerant passes upwardly through the vertical pipe 28 to the distributor head 29, and from the head 29, the refrigerant flows outwardly to the extremities of the pipes 30, where it is directed downwardly into the trough 16. The refrigerant then showers through orifices 17 directly upon the top coil of the heat exchanger member 14 and passes in a copious surface-covering volume down over the outer surface of the heat exchanger 14, running off from the bottom coil of the heat exchanger 20 into the sump B. Since the sump B is filled with liquid refrigerant to a level well above the intake orifice 26 of the Venturi tube 27, the suction created at the orifice 26, as above described, will draw a substantial quantity of the liquid refrigerant through the Venturi tube 27 and intermingling the same with the refrigerant coming from the jet of the pressure nozzle 23.

The liquid to be cooled obviously gives up and transfers to the refrigerant its heat through the walls of the heat exchanger coil 14, thereby evaporating a considerable quantity from the liquid refrigerant which is flowing down over the outer surface of the coil 14. Thus, the shell 1 becomes filled with gaseous refrigerant, which is drawn off from the top of the main vessel through the main gas return line 31. The unevaporated liquid refrigerant flows eventually into the sump B and is recirculated by means of the suction at the Venturi tube 27 up to the trough 16, whence it will again flow downwardly over the heat exchanger 14 and be partially evaporated in the course of performing its refrigeration function.

As all the high pressure liquid passing through the nozzle 23 of the jet has been subcooled in the liquid precooler coil 13, it is well deprived of flash gas and its action, when passing through the Venturi tube 27 mixed with the cold recirculated liquid through the suction orifice, is similar to that of solid water being handled. From the top member of coil 14, the liquid refrigerant runs downwardly in a large evenly distributed volume, actually flooding each consecutive coil member, partly evaporating into gas which is readily taken away at the top outlet of vessel A to the suction 55 of the compressor, while the surplus unevaporated liquid runs down into sump B to be recirculated.

The gaseous refrigerant caused by evaporation passes through the suction return line 31 to the back pressure control valve 32, which is adjusted to such a setting that the requisite amount of back pressure and the corresponding temperature in the shell 1 will be maintained. From the back pressure control valve, the suction gas passes 60 first through the stop valve and thence to the intake line 34 of a conventional refrigeration machine, wherein the gas is ultimately condensed, and returned in a continuous cyclic manner to the precooler coil in liquid state.

In order to guard against undue pressure, an auxiliary gas by-pass line 35 is provided, which conducts the gaseous refrigerant to the pressure release valve 36, set to relieve against any undue pressure above a prescribed maximum.

In order to maintain liquid refrigerant in the sump B constantly at a level substantially above the intake orifice of the Venturi tube 27, a liquid refrigerant supply line to the sump B is provided, which preferably is controlled by a suitable conventional float valve mechanism. It is also obvious that proper insulation covering be placed about the outside of the shell 1 to prevent heat influx from the outside or room temperatures.

In the event a greater recirculating head is required or greater pressure differentials are to be employed in the apparatus, it may be desirable to utilize a multi-stage Venturi tube system such as that shown in Figure 3 or modified in progressive series, so that the tubes are in line with the flow, as previously described. The operation of this multi-stage system is substantially similar to the operation of the single-stage Venturi tube system above described.

In any pipe cooling system, whether it be of the single or double pipe type or whether it be of the plain expansion valve or flooded evaporator type, the refrigerant inside must evaporate into gas in order to effect the required cooling. This gas necessarily must travel through the whole length of the coil to reach the suction outlet connection. For this reason, the coefficient of heat transfer is necessarily reduced whenever the refrigerant is inside of evaporating coils, since gas is a poor conductor of heat. In the present invention, the liquid refrigerant is showered copiously over the outside, setting free in a large vessel any vaporized liquid without impairing in any way the efficiency of the cooling surface on its rapid downward travel, whereby a very high refrigerating efficiency is secured. The high efficiency obtained in the present invention is furthermore made possible by recirculating continuously cold liquid refrigerant over the cooling coil either in the manner previously described or by circulating pumps or any other means providing for the circulation of the liquid refrigerant over the outside of the heat exchange coil or coils in a copious manner as previously described.

As there exists in any refrigerating plant a pressure differential between the high or condenser-pressure and the low or suction-pressure, this condition is utilized in connection with a jet and Venturi tube for circulating or pumping cold liquid from a sump with precooled high-pressure liquid through a jet over a heat exchanger coil.

It will readily be understood that a large quantity of liquid refrigerant is flooded voluminously over the outer surface of the heat exchange coil 14 without the slightest interference from any vaporized gas, as this emits immediately into the vessel or shell 1, while the whole heat exchange surface of coil 14 remains covered with solid cold liquid on its rapid downward travel, thus giving the effective cooling surface the highest efficiency possible. While previously comparison has been made with evaporators of the pipe or coil type, employing the refrigerant inside of the pipe or coil, another system of evaporator is that of the shell and tube type. In this evaporator, the liquid refrigerant is on the outside of the tubes, which are closely assembled inside of a vessel. The shell of this evaporator is generally three-fourths filled with liquid refrigerant, thus allowing gas space in the upper section of the cooler where suction connection is made to the compressor. During the process of evaporation, gas bubbles

are formed around the outside of the tubes, which eventually rise into the upper section of the cooler where the gas is taken away by the compressor suction. This forming of gas bubbles around the tubes continues as long as the cooler is in operation, thus impairing the heat transfer, while through the tubes in the upper section of the cooler on account of not being submerged, the gas of the refrigerant necessarily becomes superheated.

In the present cooler, the gas enters the suction to the compressor without any superheat but in saturated condition at a temperature corresponding to its back pressure. The foregoing description will also explain the extraordinary high heat transfer obtained by test.

In cooling liquids, such as milk or beer, it becomes necessary to shut down the cooling apparatus for permitting convenient cleansing of the interior of the heat exchanger coil 14. On such occasions, the valves to the compressor system are shut off and the drain valve 38 is opened to drain out all liquid refrigerant, which valve may be connected to a liquid refrigerant storage system of lower suction pressure or to another evaporator of lower back pressure to facilitate quick evacuation instead of pumping out, so that no liquid refrigerant is lost. The pressure relief valve is provided as a special safety measure, so that any pressure within the main shell 1 will be released. It then is possible to pass hot cleaning or sterilizing liquids through the heat exchanger coils to cleanse and renovate them. It is also possible to steam out the heat exchanger coil and scrub the same out with a suitable brush ball. Since the heat exchanger coil is of unitary construction and has a helical shape, there are no return bends therein, so that the cleaning or sterilizing solution will pass therethrough rapidly and quickly. Furthermore, the expansion which normally takes place in a metal structure of this character will not distort the coil because of its helical shape, thus steam or hot cleaning and sterilizing solutions may be employed without danger of causing leaks or permanent distortion in the heat exchanger coil.

Another of the many advantages of the cooler lies in its almost instantaneous application of refrigeration for starting and its immediate ceasing of the refrigerating effect after shutting down and evacuation of the cooler.

If the liquid refrigerant is circulated by a mechanically actuated pump, its suction connection is preferably made to the side of the oil drop leg 37, while the pump discharge is connected to the distributor head 29. Pressure differential means for circulation may be applied simultaneously with that of the pump, alternately or singly, as the case may be.

The apparatus and its many advantages will be clearly understood from the foregoing description, and it is obvious that numerous changes may be made in the form, construction, arrangement, and combination of the several parts of the structure may be made and substituted for those herein shown and described without departing from the spirit and nature of the invention.

Having thus described my invention, what I claim and desire to secure by Letters Patent is,—

1. A fluid cooling apparatus comprising an expansion chamber, heat exchanger means disposed within the expansion chamber, means for passing

liquid refrigerant over the outer surface of the heat exchanger means for evaporating some of the refrigerant to produce cooling in the heat exchanger means, sump-forming means for collecting the unevaporated liquid refrigerant, and differential pressure control means disposed entirely within the sump-forming means for recirculating the unevaporated liquid refrigerant over the heat exchanger means.

2. A fluid cooling apparatus comprising heat exchanger means, means for passing liquid refrigerant over the outer surface of the heat exchanger means for evaporating some of the refrigerant to produce cooling in the heat exchanger, said last means including a precooler coil positioned in proximity to the said heat exchanger means, means for collecting the unevaporated liquid refrigerant, and differential pressure control means for recirculating the unevaporated liquid refrigerant over the heat exchanger means.

3. A fluid cooling apparatus comprising an expansion chamber, heat exchanger means disposed within the expansion chamber, means for passing liquid refrigerant over the outer surface of the heat exchanger means for evaporating some of the refrigerant to produce cooling in the heat exchanger means, sump-forming means for collecting the unevaporated liquid refrigerant, and differential pressure control means disposed entirely within the sump-forming means including a high pressure nozzle and Venturi tube for recirculating the unevaporated liquid refrigerant over the heat exchanger means.

4. A fluid cooling apparatus comprising an expansion chamber, a unitary one piece heat exchanger disposed within the expansion chamber, means for passing liquid refrigerant over the outer surface of the heat exchanger means for evaporating a quantity of refrigerant to produce cooling in the heat exchanger, a sump for collecting the unevaporated liquid refrigerant, and differential pressure control means disposed within the sump including a Venturi tube for recirculating the unevaporated liquid refrigerant over the heat exchanger means.

5. A fluid cooling apparatus comprising an expansion chamber, liquid refrigerant conduit means, heat exchanger means within the chamber, means connected to the conduit means for passing liquid refrigerant to the conduit means for passing liquid refrigerant over the outer surface of the heat exchanger means for evaporating some of the refrigerant to produce cooling in the heat exchanger means, a sump for collecting the unevaporated liquid refrigerant, and pressure differential means disposed within the sump and co-operatively associated with the conduit means for introducing unevaporated liquid refrigerant into the conduit means for recirculating the unevaporated refrigerant.

6. A fluid cooling apparatus comprising an expansion chamber, liquid refrigerant conduit means, heat exchanger means within the chamber, means connected to the conduit means for passing liquid refrigerant over the outer surface of the heat exchanger means for evaporating some of the refrigerant to produce cooling in the heat exchanger means, a sump for collecting the unevaporated liquid refrigerant, and pressure differential means disposed within the sump including a Venturi tube co-operatively associated with the conduit means for introducing unevaporated liquid refrigerant from the sump into

the conduit means for recirculating the unevaporated refrigerant.

7. A fluid cooling apparatus comprising an expansion chamber, a heat exchanger disposed within said chamber, refrigerant supply means for maintaining a flow of liquid refrigerant over the outer surface of the heat exchanger, pressure control means operatively associated with the expansion chamber, said pressure control means and said refrigerant supply means being mutually adapted for relative adjustment for maintaining a predetermined gaseous liquid phase relationship for the refrigerant within the evaporator, and pressure differential means disposed entirely within the chamber for recirculating liquid refrigerant over the surface of the heat exchanger.

8. A fluid cooling apparatus comprising an expansion chamber, a heat exchanger disposed within said chamber, refrigerant supply means for maintaining a flow of liquid refrigerant over the outer surface of the heat exchanger, pressure control means operatively associated with the expansion chamber, said pressure control means and said refrigerant supply means being mutually adapted for relative adjustment for maintaining a predetermined gaseous liquid phase relationship for the refrigerant within the evaporator, pressure differential means for recirculating liquid refrigerant over the outer surface of the heat exchanger, means for collecting the liquid refrigerant from the expansion chamber, and differential pressure actuated means disposed entirely within the chamber for recirculating said collected liquid refrigerant over the heat exchanger means.

9. A fluid cooling apparatus comprising an expansion chamber, a heat exchanger disposed within said chamber, refrigerant supply means for maintaining a flow of liquid refrigerant over the outer surface of the heat exchanger, pressure control means operatively associated with the expansion chamber, said pressure control means and said refrigerant supply means being mutually adapted for relative adjustment for maintaining a predetermined gaseous liquid phase relationship for the refrigerant within the evaporator, pressure differential means for recirculating liquid refrigerant over the outer surface of the heat exchanger, means for collecting the liquid refrigerant in the expansion chamber, and high pressure nozzle and Venturi tube means disposed entirely within the chamber for recirculating said collected liquid refrigerant over the heat exchanger means.

10. A fluid cooling apparatus comprising an expansion chamber, a helical coil heat exchanger disposed within said chamber, refrigerant supply means for maintaining a flow of liquid refrigerant over the outer surface of the heat exchanger, and pressure control means operatively mounted in the expansion chamber, said pressure control means and said refrigerant supply means being mutually adapted for relative adjustment for maintaining a predetermined gaseous liquid phase relationship for the refrigerant within the evaporator.

11. A fluid cooling apparatus comprising an expansion chamber, a heat exchanger coil disposed within said chamber, refrigerant supply means for maintaining a flow of liquid refrigerant over the outer surface of the heat exchanger coil, pressure control means operatively mounted in the expansion chamber, said pressure control means and said refrigerant supply means being

mutually adapted for relative adjustment for maintaining a predetermined gaseous liquid phase relationship for the refrigerant within the evaporator, and control means for evacuating the liquid refrigerant from the expansion chamber.

5

12. A fluid cooling apparatus comprising a main shell, a sump shell disposed at the bottom of, and communicating with, the main shell, a heat exchanger disposed within the main shell, inlet means for introducing liquid refrigerant into the main shell, refrigerant pressure control means, a precooler coil connected at its one end to said inlet means and at its other end to the refrigerant pressure control means, and refrigerant distribution means connected to said pressure control means, said refrigerant distribution means including a trough for receiving a static head of liquid refrigerant and having a plurality of outlet orifices in the bottom thereof located in juxtaposition to the heat exchanger for directing a flow of liquid refrigerant over the outer surface of the heat exchanger.

13. A fluid cooling apparatus comprising a main shell, a sump shell disposed at the bottom of, and communicating with, the main shell, a heat exchanger disposed within said main shell, inlet means for introducing liquid refrigerant into the main shell, refrigerant pressure control means, a precooler coil connected at its one end to said inlet means and at its other end to the refrigerant pressure control means, refrigerant distribution means connected to said pressure control means, said refrigerant distribution means including an annular U-shaped trough for receiving a static head of liquid refrigerant and having a plurality of outlet orifices so arranged as to provide an even distribution, and means cooperatively associated therewith for directing a flow of liquid refrigerant downwardly to the top of the heat exchanger and over the outer surface thereof.

14. A fluid cooling apparatus comprising a main shell, a sump shell disposed at the bottom of, and communicating with, the main shell, a heat exchanger disposed within the main shell, inlet means for introducing liquid refrigerant into the main shell, refrigerant pressure control means, a precooler coil connected at its one end to said inlet means and at its other end to the refrigerant pressure control means, refrigerant distribution means connected to said pressure control means, said refrigerant distribution means including a trough for receiving a static head of liquid refrigerant and having a plurality of outlet orifices in the bottom thereof located in juxtaposition to the heat exchanger for directing a flow of liquid refrigerant over the outer surface of the heat exchanger, and auxiliary liquid refrigerant supply means for introducing liquid refrigerant directly into the sump shell.

15. A fluid cooling apparatus comprising a main shell, a sump shell disposed at the bottom of, and communicating with, the main shell, a heat exchanger disposed within the main shell, inlet means for introducing liquid refrigerant into the main shell, refrigerant pressure control means, a precooler coil connected at its one end to said inlet means and at its other end to the refrigerant pressure control means, refrigerant distribution means connected to said pressure control means, said refrigerant distribution means including a trough for receiving a static head of liquid refrigerant and having a plurality of outlet orifices in the bottom thereof located in juxtaposition to the heat exchanger for directing a flow of liquid refrigerant over the outer surface of the heat exchanger.

60

65

70

75

flow of liquid refrigerant over the outer surface of the heat exchanger, auxiliary liquid refrigerant supply means for introducing liquid refrigerant directly into the sump shell, and means co-

5 operatively associated with the last-named means for maintaining the supply of liquid in the sump shell constantly at a predetermined level.

16. A fluid cooling apparatus comprising a main

10 shell, a sump shell disposed at the bottom of, and communicating with, the main shell, a helical heat exchanger disposed within the main shell, inlet means for introducing liquid refrigerant into the main shell, refrigerant pressure control

15 means, a precooler coil connected at its one end to said inlet means and at its other end to the refrigerant pressure control means, said precooler coil being disposed concentrically inside the heat exchanger, and refrigerant distribution means connected to said pressure control means, said

20 refrigerant distribution means including a trough for receiving a static head of liquid refrigerant and having a plurality of outlet orifices in the bottom thereof located in juxtaposition to the heat exchanger for directing a flow of liquid refrigerant over the outer surface of the heat ex-

25 17. A fluid cooling apparatus comprising an expansion chamber, heat exchanger means within the chamber, a refrigerant conduit extending

30 into and terminating interiorly of the chamber, said conduit being provided at its terminal end with an orifice arranged for spraying refrigerant over the exterior of the heat exchanger means, means in the chamber for collecting the excess refrigerant after passage thereof over the heat exchanger means, and pressure differential means within the chamber and forming a part of the conduit for drawing the excess refrigerant into the conduit and redirecting the same over the

35 40 heat exchanger means with incoming fresh refrigerant.

18. In a fluid cooling apparatus, an expansion chamber, a heat exchanger disposed within said

45 expansion chamber having relatively small displacement with respect to the expansion chamber, and means for copiously flowing a stream of volatile liquid refrigerant over the outer surface of the heat exchanger for the maintenance thereon of a substantially uninterrupted film, whereby

50 to provide intimate contact between the film and the surface of the heat exchanger by preventing

the formation of any substantial insulating gaseous layer between the film and the surface of the heat exchanger.

19. In a fluid cooling apparatus, an expansion chamber, a heat exchanger disposed within said expansion chamber having relatively small displacement with respect to the expansion chamber, and refrigerant distributing means disposed within said expansion chamber in juxtaposition to the heat exchanger means for flowing vaporizable liquid refrigerant over the outer surface of the heat exchanger means in a substantially uninterrupted and continuous film whereby to produce evaporation at the outer surface of the film and heat exchange through the body of the film. 15

20. In a fluid cooling apparatus, an expansion chamber, a heat exchanger disposed within said expansion chamber having relatively small displacement with respect to the expansion chamber, refrigerant distributing means disposed within said expansion chamber in juxtaposition to the heat exchanger means for flowing vaporizable liquid refrigerant over the outer surface of the heat exchanger means in a substantially uninterrupted and continuous film whereby to produce evaporation at the outer surface of the film and heat exchange through the body of the film, 20 means for collecting the excess refrigerant after it has passed over the heat exchanger, and means for returning said excess refrigerant to the distributing means for recirculation. 25

21. The method of cooling liquid comprising confining the liquid to be cooled in a walled container, and flowing vaporizable liquid refrigerant over the entire heat exchange surfaces of the container in a continuous sheet, whereby to produce evaporation at the outer surface of the film and heat exchange through the body of the film. 35

22. The method of cooling liquid comprising confining the liquid to be cooled in a walled container, and flowing a vaporizable refrigerant over the exterior surface of the container in sufficient quantity to maintain a sheet of liquid refrigerant on the surface of the walled container to produce evaporation at the outer surface of the film and prevent any substantial vaporization of refrigerant at the surface of the walled container whereby to cause heat exchange through the body of the film. 45

GEORGE M. KLEUCKER. 50
